UNITED STATES PATENT OFFICE.

PETER G. GIROUD, OF BINGHAMTON, NEW YORK, ASSIGNOR TO THE INTERNATIONAL TIME RECORDING COMPANY, OF NEW JERSEY.

TIME-RECORDER.

SPECIFICATION forming part of Letters Patent No. 678,777, dated July 16, 1901.

Application filed October 9, 1900. Serial No. 32,475. (No model.)

To all whom it may concern:

Be it known that I, PETER G. GIROUD, a citizen of the United States, and a resident of Binghamton, in the county of Broome and State of New York, have invented a new and useful Improvement in Time-Recorders, of which the following is a specification.

My invention relates to a time-recorder, with the object in view of providing effective means for advancing the minute-wheel at the beginning of a new hour promptly up to the position of zero, which it should occupy in order that the record of the succeeding hour may never be coupled with the fifty-ninth minute of the preceding hour.

A practical embodiment of my invention is represented in the accompanying drawings, in which—

Figure 1 represents a section from front to rear through so much of the recording mechanism as is necessary to illustrate my invention, showing the means employed for causing the minute-wheel to jump its space. Fig. 2 represents the said portion of the recording mechanism in front elevation. Fig. 3 is a view in detail showing the reverse side of the wheel for causing the minute-printing wheel to skip and the actuating parts in immediate contact therewith; and Fig. 4 is a section in detail through the support of the drive-wheel which engages the minute-printing wheel, showing the manner in which it is mounted.

The year-wheel is denoted by *a*, the meridian-wheel by *b*, the minute-wheel by *c*, the hour-wheel by *d*, the day-wheel by *e*, and the month-wheel by *f*.

The meridian and hour wheels *b* and *d* are connected to rotate together and are driven by means of lantern-teeth *g*, projecting from the side of the rim of the meridian-wheel *C*, while the minute-wheel *c* is mounted to move independently of the meridian and hour wheels and is driven by means of a gear-wheel *h*, fixed to rotate therewith.

As my present invention is limited to the means for causing the minute-wheel *c* to promptly assume the position of zero at the beginning of the hour or at the moment the number representing the succeeding hour is moved into position, I have shown the mechanism which immediately coacts therewith,

and leave it to be understood that the several wheels are to be actuated by such approved means as have been devised therefor. In the present instance the spring-actuated lever *i*, with its pivoted nose or driving-pawl *i'* for actuating the meridian and hence the hour wheel, carries a laterally-projecting pin *j*, in position to strike the slanting face of a projection *k* on the side of the gear-wheel *l*, which intermeshes with and drives the gear *h* on the minute-wheel *c*, the face of the projection *k* on the drive-wheel *l* being extended at an angle to a radial line, and in such direction that when the pin *j* strikes it during the inward movement of the lever *i* it will force the gear-wheel *l* forward a distance sufficient to drive the minute-wheel *c* fully up to the position of zero—viz., the position which it should occupy at the beginning of the hour. The slanting surface of the projection *k* is so placed upon the wheel *l* that it will be in position to be engaged by the pin *j* on the lever *i* when the lever is allowed by the cam *m* on the actuating-shaft *n* to move forward or inward under the impulse of its actuating-spring *o* to advance the meridian and hour wheels. The sudden forward jump of the minute-wheel takes place, therefore, at the moment the hour-wheel presents the next succeeding hour, and hence if there is the slightest tendency of the minute-wheel to drag and still present the fifty-nine number of minutes instead of the zero number with which the hour begins it (the minute-wheel) will be promptly forced out of its backward position and up to the position which it should occupy at the beginning of the new hour.

The specific structure and arrangement of parts by which the drive-wheel *l* is permitted to jump forward under the impulse of the pin *j* against the projection *k* is as follows: The wheel *l* is loosely mounted on the reduced end of a hub *p*, secured to the shaft *n* by a set-screw *q*. The wheel is held in position on the reduced end of the hub *p* by means of a collar *r*, fixed on the shaft by means of a set-screw *s*, with its inner face against the end of the hub *p*, leaving a sufficient space between a flange on its inner face and the flange on the hub *p* for the free rotary or rocking movement of the wheel *l*.

The flange *t* on the inner end of the collar *r* is provided with a short recess *u* to receive a laterally-projecting pin *v*, fixed to the wheel *l*. The pin *v* within the recess *u* limits the 5 rocking movement of the wheel *l*, while permitting it to move relatively to its hub a distance sufficient to jump it forward the extent desired at the end of the hour. The said wheel *l* is normally held with its pin *v* 10 against the rear wall of the recess *u* by means of a spring *w*, fixed at *x* to the periphery of the collar *r* and having its free end *y* hooked over the pin *v*.

In operation when the lever *i* moves inwardly at the end of the hour and strikes its pin *j* against the face of the projection *k* on the wheel it forces the wheel *l* forward to the limit of its hour position, the spring *w* yielding to permit the pin *v* to move toward 15 the forward wall of the recess *u*. In this position the wheel *l* will rest until the shaft *n*, carrying the collar *r*, has been rotated by the action of the time mechanism (not shown) to bring the rear wall of the recess *u* again 20 in contact with the pin *v*, when the wheel *l* will be driven continuously by the shaft *n*, as usual, until the completion of another hour, when the forward jump will again take place, provided the wheel *m* chances to be in 25 the slightest degree backward of the position which it should occupy at the end of the hour. This provision for securing with certainty the proper record of the minute-wheel at the beginning of the hour is a very important one, since it provides against the 30 possibility of the record at the beginning of the hour presenting the new hour and fifty-nine minutes instead of the new hour and no minutes, a defect which when it occurs, 35 as it has been known to repeatedly, becomes serious in estimating the time of the workmen.

It is obvious that changes might be resorted to in the form and arrangement of the several parts without departing from the 40 spirit and scope of my invention. Hence I do not wish to limit myself strictly to the structure herein set forth; but—

What I claim is—

1. The combination, with an hour-wheel

and means for moving it step by step, of a 50 minute-wheel and means for moving it continuously, the said minute-wheel being free to be temporarily shifted independently of its continuous movement, and the driving mechanism of the minute-wheel being under the 55 control of the driving mechanism of the hour-wheel to be shifted by said hour-wheel-driving mechanism simultaneously with the step movement of the hour-wheel, substantially as set forth.

2. In combination, an hour-wheel, means for moving the hour-wheel step by step, a minute-wheel, a drive-wheel for imparting a continuous rotary movement to the minute-wheel, the said drive-wheel being mounted to 60 rotate to a limited extent independently of its support, and a spring for holding the said drive-wheel normally at one extreme of its limited movement, the said drive-wheel being under the control of the hour-wheel-driving mechanism to be rocked independently of its support against the tension of said spring, 65 substantially as set forth.

3. The combination with the hour-wheel and means for operating it step by step, of 70 the minute-wheel, a drive-wheel for continuously rotating the minute-wheel, a supporting-shaft, a hub having a bearing for loosely mounting the drive-wheel thereon, means for fixing the hub to the shaft, a collar for holding the drive-wheel on the hub and limiting its rotary movement independent of its support and a spring attached to the collar and wheel for holding the wheel normally at one 75 extreme of its said limited movement, the 80 said drive-wheel being under the control of the hour-wheel-driving mechanism to be rocked relatively to its support, substantially as set forth.

In testimony that I claim the foregoing as 85 my invention I have signed my name, in presence of two witnesses, this 5th day of October, 1900.

PETER G. GIROUD.
